WEB PRINTING PRESS

Henry A. Wise Wood, New York, N. Y., assignor
to Wood Newspaper Machinery Corporation,
New York, N. Y., a corporation of Virginia

Application March 5, 1931, Serial No. 520,291
Renewed January 30, 1934

8 Claims. (Cl. 270—5)

The present invention relates to web printing presses and has for an object to provide a novel arrangement of single impression and multiple impression printing units.

5 A particular object of the invention is to provide means for manufacturing a partly colored and partly black and white newspaper.

Another object of the invention is to provide 10 an arrangement of plates in the printing units such that in a "collect product" one section may be printed in black and another in black and other colors.

In carrying out the present invention, I may 15 employ an arrangement of printing units similar to that described in my copending application Serial No. 512,029, filed January 29, 1931, wherein a single color perfecting press unit is surmounted by a multi-color printing unit, the latter having one impression cylinder and a plurality of plate cylinders cooperating therewith, so that a web passing successively through the 20 two units will receive black impressions on both faces thereof with color impression on one of said faces.

25 The present invention provides a manner of plating two such combined units so as to produce novel and attractive results.

Other objects and advantages of the present 30 invention will appear in the following description of a preferred embodiment and thereafter the novelty and scope of the invention will be pointed out in the claims.

The accompanying drawing is a largely dia- 35 grammatic side elevation of an embodiment of my invention illustrating a typical plate arrangement.

40 Mounted on a bed plate 10 is a set of printing units A and B occupying a lower level, while at an upper level directly above these units are two printing units C and D. The units A and B are substantially alike, each being a perfecting unit comprising two pairs of printing couples. The first printing couple is composed of an impression cylinder 11 and plate cylinder 12, while 45 the second couple is composed of an impression cylinder 13, and plate cylinder 14. Each plate cylinder is provided with a novel inking system indicated generally by the reference numeral 15. A motor 16 is mounted on each of these units 50 driving the same through a belt 17 running from a sprocket 18 on the motor shaft to a sprocket 19 on the shaft of the impression cylinder 11.

The units C and D mounted respectively above 55 the units A and B, are alike, each being adapted to print a plurality of colors. Thus, each of the units C and D comprises an impression cylinder 20 cooperating with which are four plate cylinders 21, 22, 23 and 24 respectively. Each 60 of these plate cylinders is provided with its own

inking system 25. Each of the units C and D is driven by the motor 18 directly thereunder through a belt 26 running to a sprocket wheel 27. The latter is connected through a reversing clutch, not shown, to the impression cylinder 20 whereby said cylinder may be turned in reverse direction with respect to the impression cylinder 11.

A web W is passed through the units A and C, successively. The web is lead from a suitable supply through a slot in the bed plate 10, about a roll 30 to the first printing couple 11—12. The web after passing through this couple is led about a compensating roll 31 and then through the second printing couple 13—14. A set of guide rolls 32, 33, 34 and 35 leads the web about the motor 16 to the impression cylinder 20 of the unit C. Here the web passes in the direction of the arrow about the cylinder 20 to receive impressions from the plate cylinders 21, 22, 23 and 24. Thence it is guided by a set of rolls 36, 37, 38, 39, 40 and 41 to a drag roll 42. Here it is slit by slitter roll 43 and one half web W¹ after passing about a set of compensating rolls 44 is passed under a roll 45 and thence over a drag roll 46 to the folder 47. The other half web W² is turned under the web W¹ by means of turning bars 48 and then after passing about a set of compensating rolls 49 is led under a roll 50 to the drag roll 46.

Another web w may be similarly passed through the units B and D in succession. However, in the particular arrangement shown in the drawing, the web w is not lead through the printing couple 13—14, but runs directly from the roll 31 to the roll 32 and thence is carried clear of the motor 16 and to the unit D. After passing about the impression cylinder 20 of the unit D the web w is led to a drag roll 51, where it is slit into two half webs w¹ and w² by means of a slitter roll 52. The web w¹ after passing about suitable compensating rolls is led under a guide roll 54 to the drag roll 46. The web w² is turned under the web w¹ by means of turning bars 55 and then after passing about compensating rolls 56 is led under the roll 57 to the drag roll 46. Thus, all of the webs W¹ and W² and w¹ and w² are fed as a unit to the folder 47.

Variations in the arrangement of multi-color and single-color pages may be obtained by various arrangements of the plate cylinders of the units.

In the drawing, we have shown, in the unit A, printing plates P on both diametric halves of the plate cylinder 12, while there is a plate P on only one diametric half of the plate cylinder 14. Hence, one face of the web W will receive impressions on successive sections from the plate cylinder 12, while the cylinder 14 will print sections of the other face of the web alternating 60

with intervening blank sections. It will be observed that the web *W* receives impressions from the multi-color unit on the face which is printed by the couple 13—14. The plate cylinders 21, 5 22, 23 and 24 of unit C are each provided with plates on only half of the cylinder and the position of these plates is such as to print only on the blank sections between the parts printed by the plate of cylinder 14. By this arrangement, 10 it is possible to print the web in a single color, say black on one face thereof and on the other face alternately in black and in four colors. According to the plating of the cylinder 14 and the cylinders 21, 22, 23 and 24 black or color im- 15 pressions may be placed either on the odd or the even section, as desired. This permits of producing a very attractive product. For instance, four colors may be printed on the first or outside sheet of a newspaper, while the remainder 20 of the paper is printed in black.

The plating of the units B and D is somewhat different from that of units A and C, as illustrated in the drawing. In the unit B the cylinder 12 is provided with two plates *P*, while the cylinder 25 14 is left unplated. The cylinder 21 of unit D carries two plates, while the rest of the plate cylinders of unit D carry plates on only half of each cylinder. By this arrangement, the web *w* is printed on one face by the couple 11—12 and 30 then is printed on the opposite face by the couple 20—21, after which alternate sections, on the face printed by the cylinder 21, will receive multi-color impressions from the cylinders 22, 23 and 24. Thus, the web *w* may be printed in 35 black on one face while on the other face sections printed in black alone will alternate with sections printed in black and three colors. In other words, the cylinder 21 may be used for printing in black. The usefulness of this ar- 40 rangement is quite apparent. Should any damage occur to one printing couple of the units A or B, one of the cylinders in the multi-color unit can be used for perfecting in black.

The drawing shows four color cylinders being 45 used for color printing in the unit C and three for color printing and one for black in the unit D, but it is within the scope of my invention to use any number of cylinders up to the limit of the color members as desired. Instead of using 50 all four colors of the color unit, either one, two or three colors may be employed simply by the proper arrangement of plates.

Having thus described my invention, what I 55 claim as new and desire to protect by Letters Patent is, as follows:

1. A web printing press comprising, a plurality of plate cylinders adapted to impress the same face of a web, an individual inking system for 60 each cylinder, a printing plate on one half of each cylinder, the plates being relatively positioned whereby one cylinder will print spaced sections of the web and the rest of the cylinders will print in multiple colors in the intervening spaces between said sections.

2. A web printing press comprising, a plate cylinder adapted to print on one face of a web, and a plurality of plate cylinders adapted to print on the other face of the web, an individual 65 inking system for each cylinder, a printing plate on each diametric half of the first-named cylin-

der, and a printing plate on one diametric half of each of each of the other plate cylinders, the latter printing plates being so relatively positioned that one of them will print on alternate sections of the web and the rest will print in multiple colors in the spaces between said sections.

3. In a web printing press, a perfecting press unit, a multiple impression unit comprising a plurality of plate cylinders, means for passing a web through said units, certain of said cylinders having printing plates on only one diametric half thereof, said printing plates being so relatively disposed as to make multiple impressions on alternate sections of the web.

4. A web printing press comprising a single color printing unit and a multiple color printing unit, the single color printing unit comprising a pair of plate cylinders adapted to print on opposite faces of a web, one of the cylinders having a printing plate on each diametrical half thereof and the other cylinder having a plate on only one diametrical half thereof to leave blank sections on one face of the web, the multi-color printing unit having a plurality of printing cylinders 20 each having a printing plate on only one diametrical half thereof, the latter printing plates being adapted to print on said blank sections.

5. A multi-color web printing press comprising an impression cylinder and a plurality of plate 30 cylinders associated therewith, a printing plate on only one-half of each of said cylinders for printing alternate sections of a web, said plates being so relatively disposed that they will make multiple impressions on said alternate sections 35 of the web, and means for making single impressions in the sections intermediate said alternate sections.

6. A web printing press comprising, a pair of primary plate cylinders, printing plates on both circumferential halves of each cylinder and adapted to print on both sides of a web, a plurality of secondary plate cylinders, printing plates on the latter cylinders adapted to print on one side of the web only, the latter plates covering 45 only a circumferential half of the respective cylinders they are mounted on and adapted to make impressions on alternate spaced sections of the web, said impressions being superposed upon and in register with impressions made by plates 50 on one of the circumferential halves of one of the primary cylinders, and a separate inking means for each cylinder.

7. A multi-color web printing press comprising, a single impression cylinder and a plurality of printing cylinders associated therewith, printing plates on said cylinders, and a separate inking means for each cylinder, said plates being so disposed as to print in multiple colors on certain spaced sections of a web and in a single color on intervening sections.

8. A multi-color web printing press comprising, a single impression cylinder and a plurality of printing cylinders associated therewith, printing plates on both halves of one of the cylinders and a printing plate on only one half of each of the other cylinders, the plates on the cylinders being so related that they will make multiple impressions on alternate spaced sections of a web and single impressions on the intervening sections, and a 70 separate inking means for each cylinder.

HENRY A. WISE WOOD.
